(57) **CLAIM**

The ornamental design for a combined dental floss pick and dental floss container, as shown and described.

DESCRIPTION

FIG. 1 is an exploded perspective view of a combined dental pick and dental floss container showing my new design;

FIG. 2 is a front elevational view of the dental floss container thereof;

FIG. 3 is a rear elevational view of the dental floss container thereof;

FIG. 4 is a top plan view of the dental floss container thereof;

FIG. 5 is a bottom plan view of the dental floss container thereof;

FIG. 6 is a left side elevational view of the dental floss container thereof;

FIG. 7 is a right side elevational view of the dental floss container thereof;

FIG. 8 is a top plan view of the interdental pick thereof;

FIG. 9 is a bottom plan view of the interdental pick thereof;

FIG. 10 is a front elevational view of the interdental pick thereof;

FIG. 11 is a rear elevational view of the interdental pick thereof;

FIG. 12 is a left side elevational view of the interdental pick, the right side elevational view being a mirror image thereof;

FIG. 13 is a front elevational view of the dental floss container with the interdental pick in place thereof;

FIG. 14 is a rear elevational view of the dental floss container with the interdental pick in place thereof;

FIG. 15 is top plan view of the dental floss container with the interdental pick in place thereof;

FIG. 16 is left side elevational view of the dental floss container with the interdental pick in place thereof;

FIG. 17 is a fragmentary perspective view showing the dental pick partially inserted;

FIG. 18 is a fragmentary perspective showing the dental pick fully inserted;

FIG. 19 is a fragmentary perspective view showing the dental pick fully inserted and in locked position; and,

FIG. 20 is a perspective view of the dental pick; the broken lines are for environmental purposes only and form no part of the claimed design.

The pick and dental floss container are shown separately for convenience of illustration.
